of Edouard Thys and Albert K. Miller

Application August 12, 1942, Serial No. 454,484

6 Claims. (Cl. 45—82)

Our invention relates to improvements in reading stands and particularly to improvements in the means for supporting the book in inverted reading position.

An important object of the invention is to provide supporting means which can be easily and quickly adjusted by an invalid while lying on his back and using only one arm.

A further object of the invention is to provide supporting means which do not obscure the printed portion of the page.

A further object of the invention is to provide supporting means which can be quickly adjusted to accommodate various sized books by a patient using only one arm.

A further object of our invention is to provide one rigid and one movable shelf whereby short supporting means can be used which will not cover any printed matter.

A further object of our invention is to provide a combination reading stand and bed table.

Other objects and advantages of our invention will become apparent from the following description.

In the accompanying drawings forming a part of this specification, and in which like numerals are employed to designate like parts throughout the same:

Fig. 1 is a view in perspective showing a book in place in inverted position;

Fig. 2 is a view in cross-section taken on the line II—II of Fig. 1;

Fig. 3 is a view in perspective showing the device in relation to a hospital bed;

Fig. 4 is a view in perspective of the device arranged as a bed table;

Fig. 5 is a view in side elevation of the device of Fig. 4 in relation to a hospital bed;

Fig. 6 is a view in perspective of a modification;

Fig. 7 is a cross-sectional detail of the runner; and

Fig. 8 is a view in perspective of the runner.

One of the problems in providing a book rack for use by injured service men and others who are immobilized and compelled to lie on their backs for long periods is to have an arrangement of the supporting elements so that the invalid can manipulate the device with one arm and without assistance from a nurse or attendant. We have found that the device now to be described is capable of complete manipulation by the invalid with one hand.

The numeral 10 denotes a backboard, preferably flat and having a rigid shelf 11 secured along

one edge and an adjustable shelf 12 adapted to slide over its surface.

Backboard 10 is supported by means of a cross-rod 13 held in a swivel block 14, which in turn is supported by stand-rod 15, the latter being mounted in any suitable floor base member 16. The details of these last features may be varied, and backboard 10 may be supported by other means.

10 Adjustable shelf 12 is made of a length equal to the length of backboard 10 and has friction lock straps 17 secured at each end by means of screws 18 or other suitable fastenings. Each strap extends beyond backboard 10 and has a hole 20 adapted to receive a tension rod 21 threaded at one or both ends to receive a lock nut 22. By loosening lock nut 22 adjustable shelf 12 can be moved vertically over the face of backboard 10 and thus be spaced the desired distance from shelf 11 to receive a book or magazine between the two shelves. Between these two shelves extends the connector 23 fitted in holes 24, 25 in shelves 12 and 11 respectively.

Adjacent the front face of shelves 11 and 12 25 may extend a slide section or track 26 suitably secured to the shelves and having bent portions 27 and 28 adapted to receive a runner 30 having a complementary bent portion 31. Thus, runner 30 is supported in slide 26 for right and left 30 movement. While we have shown four such runners 30, a larger number could be used if holding pages which are particularly limp. Also, it is obvious that other forms of track or slide section could be substituted for section 26 used here to illustrate the combination of the invention.

Cross-rod 13 is fitted in swivel block 14 with a push fit so that when wing nut 33 is tightened, cross-rod 13 is held against movement.

40 The operation of our device is as follows: Assume that the patient desires to place in the reading stand a copy of "The Reader's Digest," which is a magazine about 5 3/8" by 7 5/8", and that the patient has but one arm free with which 45 to do it. The first step is to rest the bottom of the back binding on shelf 11 and note how high the binding extends on connector 23. Preferably connector 23 has various colored bands 50, 51, 52, 53, etc. along its length about one-half inch 50 in width, so that the patient can easily remember by color the position of the binding while taking this measurement. The next step is for the patient to lay the book down and to loosen lock nut 22 only enough so that he can move adjustable shelf 12 up or down as the case requires.

Shelf 12 is moved until its lower face comes to the correct point on connector 23. The patient then tightens lock nut 22. The next step is for the patient to open the book to about its middle and slip half of the pages in behind connector 23 so that the book hangs across and is supported by it. The next step is to close the book as it hangs suspended on connector 23 and lay it back against the right half of backboard 10. While thus holding it with the thumb, the fingers can move right-hand runner 39 on shelf 12 into position to support the leaves of the book. The right-hand runner on shelf 11 is similarly moved into position. The next step is for the patient to move the left-hand pair of runners 30 into a position spaced about the same distance from connector 23 as the right-hand runners. In this connection, and to assist in this spacing of the runners, we prefer to have various colored squares 40 marked off along the face 27 of slide sections 26. Matched color squares will be equidistant from hole 24. The patient can now easily slide the cover from under the right-hand runners 39 and move it into position behind left-hand runners 30.

Because shelf 12 can be readily adjusted with relation to shelf 11 to accommodate books or magazines of various sizes, it is possible and preferable to have runners 30 of such a dimension that they do not obscure the printed matter on the page.

Also, by having them easily moved to the right or left, the patient can easily adjust them if, during the turning of the pages, the center of the weight should shift or the pages tend to bulge and fall down.

Turning of the pages is effected by pushing the page towards the center of the book and slightly towards the board at the same time, and having thus released the page from the right-hand runners, it is turned and pushed or slid under the left-hand runners, where it remains held by them.

The modification shown in Fig. 6, instead of employing the tension rod 21, lock nut 22 and friction lock straps 17, has adjustable shelf 12 held to backboard 10 by means of threaded bolts 41 having wing nuts 42. Backboard 10 is slotted at 43 to receive bolts 41 and permit movement of adjustable shelf 12. Other than this the structure is like the one illustrated in Fig. 1.

In Figs. 4 and 5 we have shown the means by which the reading stand can be converted into a bed table. This is accomplished by leg 60 hinged to adjustable shelf 12 and leg 61 hinged to shelf 11. Legs 60 and 61 are secured by means of bolts 62 and 63 respectively and wing nuts 64 and 65. When the device is to be used as a table, lock nut 22 is loosened and adjustable shelf 12 is removed from the end of backboard 10 and replaced thereon with the shelf extending in the direction opposite to shelf 11. When legs 60 and 61 are not in use, they are folded up into the position shown in Fig. 2.

It is to be understood that the forms of our invention herewith shown and described are to be taken as preferred examples of the same and that various changes in the shape, size and arrangement of parts may be resorted to with-

out departing from the spirit of our invention, or the scope of the sub-joined claims.

Having thus described our invention, we claim:

1. In a reading stand, the combination of a backboard, a shelf secured adjacent one edge thereof, an adjustable shelf thereon, a connector extending between said shelves and spaced outwardly from said backboard, runners, and means secured adjacent the faces of said shelves for supporting said runners thereon whereby the latter may be moved toward or away from said connector.
2. In a reading stand, the combination of a backboard, a shelf secured adjacent one edge thereof, an adjustable shelf thereon, means supported by said shelves and spaced outwardly from said backboard for engaging the center portion of a book, runners, and means secured adjacent the faces of said shelves for supporting said runners thereon whereby the latter may be moved toward or away from said connector.
3. In a reading stand, the combination with a backboard of a member projecting therefrom along one edge, a second member spaced from and arranged parallel with said last-named member adapted to be moved toward or away from said last-named member, means for securing said second member in adjusted position on said backboard and slideable means secured to said first and second named members for supporting the leaves of a book held therebetween.
4. In a reading stand, the combination with a backboard of a member projecting therefrom along one edge, a second member spaced from and arranged parallel with said last-named member adapted to be moved toward or away from said last-named member, means for securing said second member in adjusted position on said backboard, a connector extending between said first and second named members and spaced away from the face of said backboard, and slideable means secured to said first and second named members for supporting the leaves of a book held therebetween.
5. In a reading stand, the combination of a backboard, a shelf secured adjacent one edge thereof, an adjustable shelf thereon, means supported by said shelves and spaced outwardly from said backboard for engaging the center portion of a book, means for supporting said backboard in convenient reading position, runners, and means secured adjacent the faces of said shelves for supporting said runners thereon whereby the latter may be moved toward or away from said connector.
6. In a reading stand, the combination with a backboard of a member projecting therefrom along one edge, a second member spaced from and arranged parallel with said last-named member adapted to be moved toward or away from said last-named member, means for securing said second member in adjusted position on said backboard, means for supporting said backboard in convenient reading position, and slideable means secured to said first and second named members for supporting the leaves of a book held therebetween.
